OUTGOING TRUNK EXTENDER APPARATUS FOR TELEPHONE OFFICE EQUIPMENT

Paul V. De Luca, Port Washington, N.Y., assignor to
Porta Systems Corp., Port Washington, N.Y.

Filed Nov. 12, 1970, Ser. No. 25,945

Term of patent 14 years

Int. Cl. D14—03

U.S. Cl. D26—14

FIG. 1

FIG. 2

FIG. 3

FIG. 4

FIG. 5

FIG. 6

FIG. 1 is a perspective view of the outgoing trunk extender apparatus for telephone office equipment embodying my new design;

FIG. 2 is a perspective view of the outgoing trunk extender apparatus of FIG. 1, with the front cover thereof in the closed position;

FIG. 3 is a top plan view of the outgoing trunk extender apparatus of FIG. 1;

FIG. 4 is a side view of the outgoing trunk extender apparatus depicted in FIG. 1;

FIG. 5 is a rear view of the outgoing trunk extender apparatus depicted in FIG. 1; and

FIG. 6 is a front view of the outgoing trunk extender apparatus with the front cover in its opened position.

I claim:

The ornamental design for an outgoing trunk extender apparatus for telephone office equipment, substantially as shown.
